UNITED STATES PATENT OFFICE.

HERBERT T. HERR, OF PITTSBURGH, PENNSYLVANIA, ASSIGNOR TO WESTINGHOUSE ELECTRIC & MANUFACTURING COMPANY, A CORPORATION OF PENNSYLVANIA.

BLADING FOR ELASTIC-FLUID TURBINES.

1,247,400.

Specification of Letters Patent. Patented Nov. 20, 1917.

Application filed February 24, 1914. Serial No. 820,536.

To all whom it may concern:

Be it known that I, HERBERT T. HERR, a citizen of the United States, and a resident of Pittsburgh, in the county of Allegheny and State of Pennsylvania, have made a new and useful Invention in Blading for Elastic-Fluid Turbines, of which the following is a specification.

This invention relates to turbine blading, and more particularly to means for securing together the outer ends of blades located in one row.

An object of this invention is to produce new and improved means for securing the outer ends of the blades of a row together for the purpose first, of forming a shroud or cover for the outer ends of the blades, and, second, for preventing objectionable vibrations in the blades.

20 These and other objects I attain in a blade embodying the features herein described and illustrated in the single sheet of drawings accompanying and forming a part of this application.

25 In the drawings:

Figure 1 is a fragmental, sectional view of a rotor element of a turbine equipped with a single blade;

Fig. 2 is a fragmental, transverse, sectional view of a blade-mounting element diagrammatically shown and equipped with blades embodying my invention;

Fig. 3 is a fragmental, perspective view of a rotor element equipped with blades embodying my invention;

Fig. 4 is a perspective view of a single blade.

One of the features of my invention is that the separate blades are provided with cover members or spacing pieces which co-operate with each other when the blades are assembled and form a shroud or cover for the blades of each row.

Another feature of my invention is that the ends of adjacent blades are firmly secured together so that several blades co-operate with each other in resisting the vibration creating strains to which the blades are subjected.

50 In the drawings I have shown a turbine blade-mounting element, which is provided with overhanging or laterally projecting

flanges 6. Each flange shown is provided with a plurality of radially extending blade-mounting slots 7 cut in its lateral face, and as illustrated, each blade 8 is provided with a substantially T-shape shank 9 adapted to be inserted into one of the slots 7 so that its cross bar 10 engages the inner face of the flange and thereby holds the blade in place on the blade-mounting element and prevents it from being thrown outwardly under the influence of centrifugal or any other displacing forces.

In the drawings the blades illustrated are of the type known as impulse blades, but it will be apparent that my invention may be employed with any kind or type of blades. The body portion of each blade is substantially crescent shape in cross section; that is, it is provided on one side with a concave working face 11 and on the other side with a convex forward face 12. The outer or free end of each blade is provided with an integrally formed cover or spacing piece 13, which, as illustrated in the drawings, extends approximately at right angles to the concave face 11 and overhangs that face. As illustrated, the cover or spacing piece is rectangular in shape for the purpose of facilitating the mounting of blades on the particular blade-mounting element illustrated. With this construction each blade can be separately slipped into place on the blade-mounting element by forcing its shank laterally into one of the blade-mounting slots. The slots are so spaced that the forward edge of each spacing piece 13 engages the rear edge of the next adjacent piece. As illustrated, the pieces 13 are so formed that the forward edge of each piece is slightly overlapped by the rear edge of the adjacent piece 13 when the blades are assembled. With this arrangement the spacing pieces co-operate to form a continuous shroud or cover for each row of blades, and the fluid passage between each pair of adjacent blades is closed at each end of the blade and consequently fluid passing therethrough is prevented from spilling past the outer or free ends of the blades. For the purpose of preventing the blades from vibrating, I have provided new and improved means for securing together the con-

tacting edges of the separate spacing pieces 13 so that all or a portion of the blades of one row coöperate in resisting vibration-imparting strains. In my present invention, this is accomplished by welding or autogenously soldering the contacting edges of the spacing pieces together.

In carrying out my invention I preferably so form the edges of the spacing pieces 13 that each piece slightly overlaps an adjacent piece in an assembled row of blades. In addition to this I preferably bevel the overlapping edge of each piece and provide a coöperating beveled shoulder on the overlapped piece so that V-shape and transversely extending grooves 14 are formed across the organized or assembled shroud of each row of blades. A separate piece of metal 15 is preferably placed in each of these grooves 14 and the pieces 13 may then be secured together by subjecting the strips 15 to a welding heat and thereby welding them to each adjacent or contacting piece 13.

It will, of course, be understood that the contacting edges of the spacing pieces 13 may be welded directly together without employing the accompanying strips 15. This may be accomplished in any suitable manner, such, for example, as by electric welding. After the outer ends of the blades are secured together, the outer face of the shroud may be milled or otherwise trued up if desired.

It will be understood that the configuration and location of the spacing pieces on the separate blades may be materially modified, and that the specific means for mounting the blades to the blade-mounting element may be varied, since it nor the spacing pieces 16 at the bases of the blades, are not essential to the invention.

It will also be apparent that other and various changes in detail may be made without departing from the spirit and scope of the invention as set forth by the appended claims.

Having thus described my invention, what I claim is:

1. In combination with a turbine, a blade mounting element, and a row of turbine blades mounted on said element, each blade having an integrally formed spacing piece at the outer or free end thereof, and a welding tip of reduced section integrally formed along one edge of each piece. 50 55

2. In combination with a turbine, a blade mounting element, and a row of blades mounted thereon, each blade being provided at its outer end with a substantially rectangular spacing piece having a welding edge of reduced section formed on an end thereof and adapted to engage the spacing piece of the next adjacent blade when the blades are assembled in a row. 60

3. In combination with a blade-mounting element, a row of turbine blades mounted on said element, each blade having an integrally formed spacing piece at the outer or free end thereof, said blades being so arranged that the spacing pieces of said blades engage each other, and a welding strip for securing each piece to an adjacent piece. 65 70

4. In combination with a turbine, a blade mounting element, a row of blades mounted on said element, each blade being provided at its outer end with an integrally formed cover portion, an overhanging welding tip, of reduced vertical thickness, integrally formed along one edge of each cover portion, and a tip receiving groove formed 80 along the opposite edge of each cover portion, said blades being so arranged on the element, that the tip of one cover portion engages and is welded into the groove of the cover portion of the next adjacent blade. 85

In testimony whereof, I have hereunto subscribed my name this 19th day of February, 1914.

HERBERT T. HERR.
